COMBINED NESTABLE BED AND CHEST FOR A DORMITORY

George S. Fasanella, Chicago Heights, Ill., assignor to
The Englander Company, Inc., Chicago, Ill., a corpora-
tion of New York

Filed Mar. 7, 1967, Ser. No. 6,110

Term of patent 14 years

(Cl. D33—6)

FIG. 1 is a front perspective view illustrating the appearance of a closed combined nestable bed and chest for a dormitory embodying my design;

FIG. 2 is a rear perspective view of the combined nestable bed and chest for a dormitory of FIG. 1; and

FIG. 3 is a front perspective view of the combined nestable bed and chest for a dormitory of FIG. 1, illustrating the combined nestable bed and chest for a dormitory in an open position.

I claim:

The ornamental design for a combined nestable bed and chest for a dormitory, as shown and described.
